UNITED STATES PATENT OFFICE.

CHARLES SYKORA, OF AMO, MINNESOTA.

THRESHING-MACHINE.

SPECIFICATION forming part of Letters Patent No. 786,172, dated March 28, 1905.

Application filed January 14, 1905. Serial No. 241,127.

To all whom it may concern:

Be it known that I, CHARLES SYKORA, a citizen of the United States, residing at Amo, in the county of Cottonwood and State of Minnesota, have invented new and useful Improvements in Threshing-Machines, of which the following is a specification.

My invention pertains to threshing-machines; and it contemplates the provision of a threshing-machine which is possessed of high capacity and yet is simple and inexpensive in construction and well adapted to withstand the usage to which threshing-machines are ordinarily subjected.

The invention involves the cylinder and concave and the parts adjacent thereto and cooperating therewith, and it will be fully understood from the following description and claim when taken in connection with the accompanying drawings, forming part of this specification, in which—

Figure 1 is a longitudinal vertical section of so much of a threshing-machine as is necessary to illustrate my invention. Fig. 2 is a top plan view of the same with the upper wall or top of the casing removed, and Fig. 3 is a detail view of the straw-slide of the machine.

Similar letters designate corresponding parts in all of the views of the drawings, referring to which—

A is the casing of the machine, which may be of any construction compatible with the purposes of my invention.

B is the cylinder of the machine, which *per se* may be of the ordinary or any other approved construction.

C is the concave complementary to the cylinder, which concave is preferably of the conventional type—*i. e.*, made up of transverse grate-bars *a* and teeth extending upwardly from said grate-bars and arranged to coöperate with the teeth of the cylinder B—and D is the straw-slide, which constitutes an important feature of the machine, inasmuch as

it materially contributes to the capacity thereof, as will be presently pointed out in detail. The said straw-slide D forms an extension of the rear end of the concave C—that is, extends upwardly and rearwardly from the concave—and it comprises a transverse bar *b*,

fixed to the concave C at the rear end thereof, and parallel upwardly and rearwardly extending tangs *c*, the series of which extend the full width of the cylinder and concave, as best shown in Fig. 2. From the transverse bar *b* to the free ends of the tangs the spaces *d* between the tangs are uninterrupted, and from this it follows that while the straw will freely slide up the tangs and by removing the liability of choking contribute materially to the capacity of the machine the grain will fall through the uninterrupted or continuous spaces between the tangs into the grain-pan, (indicated by E,) which grain-pan is disposed below all of the working parts of the machine, as shown.

As above stated, the uninterrupted spaces between the tangs *c* of the straw-slide D permit the grain beaten out of the straw to pass with great facility through the slide, and therefore in order to prevent loss of grain and to assure the same dropping immediately into the pan E, I provide the partition or grain-stopping board F. This partition or stopping-board is disposed behind the straw-slide D and extends the full width of the machine and from a point slightly above the upper end of the straw-slide to a point in about the same horizontal plane as the lowermost part of the concave C. The upper end or edge of the partition or board F is deflected rearwardly, as indicated by *e*, and hence will facilitate the rearward passage of the straw.

G is a rotary straw-feeder which is located above the upper ends of the slide D and board F and is designed to be rotated in the direction indicated by arrow in Fig. 1, so as to accelerate the rearward passage of straw and lessen the liability of the machine becoming choked.

H is a deflector extending downwardly and rearwardly behind the feeder G and having for its purpose to prevent the straw from flying upwardly.

I is a straw-rack disposed in rear of the upper portion of the board F; J, a comparatively long straw-rack disposed below and in rear of the rack I; K, a transversely-disposed toothed cylinder located between and adjacent to the rear end of the rack I and the for-

ward end of the rack J; L, a transversely-disposed rotary beater located above and slightly to the rear of the toothed cylinder K and comprising by preference a shaft f, radial arms g, located adjacent to the ends of said shaft, and bars h, connecting the arms g, and M is a deflector extending downwardly and rearwardly behind the beater L and, like the deflector H, having for its purpose to hold 10 the straw down on the working parts and prevent flying of the straw. In the present and preferred embodiment of my invention the said deflectors H and M are hinged so as to permit of their being positioned to suit the condition of the grain that is to be threshed, and 15 I prefer to employ the conventional means illustrated for adjustably fixing the said deflectors in the positions desired.

In the practical operation of the machine 20 I contemplate working the toothed cylinder K a little faster than the comparatively small straw-rack I, this with a view of enabling the said cylinder to pick the straw off the rear end of the said rack, and thereby contribute 25 to accelerating the rearward passage of the straw, with a view of increasing the capacity of the machine and lessening the liability of the same becoming choked. The beater L, I contemplate driving at a speed about five 30 times as fast as that of the cylinder K, with a view of enabling the said cylinder K to hold the straw back to a slight extent while the beater L pulls the said straw apart and beats all of the grain out of the same. This coöperation 35 of the cylinder K and the beater L will be appreciated as an important advantage when it is remembered that the straw is frequently massed into bunches, and unless the said bunches are thoroughly opened a large portion 40 of the grain will be carried out of the machine in the straw.

It will be appreciated from the foregoing that all of the parts of my novel threshing-machine contribute to the capacity of the machine, and yet the machine is at once simple, 45

compact, and well adapted to withstand rough usage and operate on the straw that is in bad condition.

I have specifically described the construction and relative arrangement of the parts included in the present and preferred embodiment of my invention in order to impart a definite understanding of the said embodiment. I do not desire, however, to be understood as confining myself to the said specific 50 construction and relative arrangement of parts, as such changes or modifications may be made in practice as fairly fall within the scope of my invention as claimed.

Having described my invention, what I 60 claim, and desire to secure by Letters Patent, is—

In a threshing-machine, the combination of a threshing-cylinder and concave, a straw-slide extending upwardly and rearwardly from the 65 rear end of the concave and having spaces for the downward passage of grain, a grain-stopping board arranged behind the straw-slide, a rotary straw-feeder disposed above the straw-slide and grain-stopping board, a straw-rack 70 arranged behind the upper portion of the grain-stopping board, a straw-rack arranged below and in rear of the first-mentioned rack, a rotary, toothed cylinder arranged transverse of the machine and between the rear 75 end of the first-mentioned rack and the forward end of the second-mentioned rack, a rotary beater adapted to be rotated at a higher rate of speed than the toothed cylinder and disposed above and to the rear of the same, 80 and deflectors arranged behind the rotary straw-feeder and the rotary beater.

In testimony whereof I have hereunto set my hand in presence of two subscribing witnesses.

CHARLES SYKORA.
